TENSION CONTROL SYSTEM FOR PRINTING PRESS

Henry L. McWhorter, Hinsdale, Ill., assignor to The Goss Printing Press Company, Chicago, Ill., a corporation of Illinois

Application August 14, 1952, Serial No. 304,405

1 Claim. (Cl. 242—75)

The present invention relates to web tension control systems of the type finding particular utility in web-fed printing presses.

Any tension control system essentially includes two main elements; one affected by the web tension, and the other to make a corrective adjustment. The first element is, therefore, what might be termed a sensing device responsive to tension changes in the running web. The second element, which usually comprises some form of braking means, is related to the first in that it is responsive to the operation of the first element to maintain a particular predetermined web tension or to produce an increase or decrease thereof. Thus it is apparent that the effectiveness of the entire system is largely dependent on the sensitivity and responsiveness of the first element.

Numerous devices have previously been used to perform the function of sensing web tension changes. Examples of such devices include spring biased rollers, shock absorber mounted rollers, the so-called inertia-weight biased rollers or combinations thereof. However, none of these devices has proved to be entirely satisfactory primarily because of their variable sensitivity and sluggish responsiveness. This has necessitated resort to complex auxiliary equipment for achieving adequate tension control. As a result, prior tension control systems have been cumbersome, liable to malfunction, and not susceptible of economical manufacture.

Accordingly, it is the general object of the invention to overcome the disadvantages of the prior tension control systems through the provision of a novel tension control system of an exceedingly simple character comprising relatively few components as compared to prior art devices, thus minimizing initial cost and maintenance expense, and which is highly sensitive to changes in web tension and quickly responsive to correct the same.

The object of the invention thus generally set forth, together with other and ancillary advantages, are attained by the construction and arrangement shown by way of illustration in the accompanying drawings, in which:

Figure 1 is a fragmentary side elevation of an automatic paper reel assembly for supplying paper to a web-fed printing press and including a tension control system embodying the features of the present invention.

Fig. 2 is a diagrammatic representation of the tension control system shown in Fig. 1.

Fig. 3 is a diagrammatic representation of a press speed controller showing an auxiliary contact mechanism associated therewith.

Referring more particularly to Fig. 1 of the drawings, there shown is an automatic paper reel assembly for a web-fed printing press. It includes a pair of spaced upright supporting frames 10 of generally Y-shape upon which is supported a paper reel generally designated 11. The reel 11 is of the type comprising a pair of spaced, three-arm spiders 12 for the support of spindles 13 upon which are rotatably mounted rolls of paper 14. The reel 11 includes a central shaft 15 on which it is adapted to be rotated by means of a motor 16 and a suitable gear

2

train, generally designated 17, enclosed within a housing 18 to index the paper rolls 14 supported thereby between loading, reserve, and operative feeding stations.

Mounted on the supporting structure is a pre-drive assembly indicated generally at 20 for bringing the reserve paper roll up to press speed prior to making a paster to supply the web from it to the press upon expiration of the paper roll in the operative feeding station. The pre-drive assembly includes belts 21 running about spaced pulleys 22 and 23 and is adapted to be moved into engagement with the peripheral surface of the reserve roll by means of a pneumatic actuator 24. The belts 21 are adapted to be driven by means of an endless belt between the pulley 23 and a differential mechanism indicated generally at 26, the latter being driven from the main press drive shaft (not shown).

Indicated also in Fig. 1 of the drawing, in phantom outline, is a paster assembly 30 operative to effect the joining of the running web W with the leading end of the paper on the reserve paper roll as the running web roll is about to expire. The paster assembly 30, per se, forms no part of the present invention. For the details thereof, reference is made to applicant's copending application Serial No. 239,542, filed July 31, 1951, now United States Patent No. 2,689,095. Suffice it to say for present purposes that the paster assembly 30 includes a carriage 31 journaled on a shaft 32 for swinging movement toward and away from the reel assembly by means of pneumatic piston and cylinder actuator 33. A set of web deflecting brushes 34 are rockably supported on the carriage 31 for movement into and out of web engaging position by means of a pneumatic actuator 35. The web deflecting brushes 34 are adapted to press the running web into engagement with the new roll of paper so as to effect a paster upon indexing the new roll from the reserve station upon expiration of the paper roll occupying the operative feed station. After the paster has been made, the old web must be severed, and for this purpose the paster assembly 30 is equipped with a tail cutter 36.

In carrying out the present invention a floating roller 40 engaging in a loop in the running web W and suspended for lateral movement into and out of the loop, with the movement thereof severely limited, is utilized as a web tension sensing device. The limitation of movement, as will be seen, enables the inertia effect of the floating roller to be substantially eliminated. The roller serves to regulate the application of pressure fluid to a hydraulic piston and cylinder actuator 42 by controlling the operation of a pressure regulator 46. The actuator 42 is operative to determine braking force applied by a stationary tension belt 44 to the paper roll 14.

Referring more particularly to the drawings, the web W is fed from the paper roll 14 occupying the operative feeding station and is passed about a cocking roller 48 which is adjustably supported in position for appropriate movement to remove diagonal stress lines from the running web. From the cocking roller, the web has a U-shaped loop formed therein in the bight of which is disposed the floating roller 40. From the floating roller the web passes about a guide or lead-in roller 49 and then upwardly to the printing press (not shown).

The belt actuator 42 comprises a hydraulic piston 50 and cylinder 51 to effect a pull on the tension belt 44. To this end the actuator includes a pair of pulleys 52 and 53, respectively fixed to the supporting structure 10 and to the piston 50 and about which the belt 44 is looped. While in the drawings only one belt is shown for illustrative purposes, in practice four belts are provided so as to accommodate full and fractional width paper rolls. As shown, the belt is resiliently anchored at its lower end at 44a adjacent the bases of the supporting frames 10, and passes about a guide roller 54 disposed between the

lower ends of the Y-frames 10 and inwardly of the axis of the running web roll spindle 13. From the guide pulley 54 the belt 44 passes outwardly and upwardly about the periphery of the running web roll 14, and thence about the fixed pulley 52. From the fixed pulley the belt is looped about the tension pulley 53 and has its upper end anchored to the supporting structure. This belt and pulley arrangement causes the belt to frictionally engage the periphery of the running web roll and thus apply a braking force thereto. Movement of the piston within the cylinder so as to extend or retract the tension pulley 53 determines the amount of braking force applied by the belt to the periphery of the running web roll.

It will be apparent that the piston 50 divides the cylinder 51 into two chambers 51a and 51b, which, for convenience, will be referred to as the "tension-increase" and "tension-decrease" chambers, respectively. Thus upon supplying pressure fluid to the tension-increase chamber the piston is extended, thereby moving the tension pulley 53 outwardly (to the right) to effectively tighten the belt and increase frictional engagement thereof with the periphery of the running web roll. Movement of the tension pulley inwardly results in a decrease of the braking force.

The supply of pressure fluid to the belt actuator 42, as previously noted, is under the control of pressure fluid regulating means, designated generally at 46. In the illustrative embodiment of the present invention, this means includes a jet pipe 55 enclosed within housing 56 and pivoted at 57 for lateral movement between tension-increase and tension-decrease positions. Pressure fluid is supplied to the jet pipe by way of a line 58 from a pump 59 which in turn draws its supply from a sump 60. Supply line pressure is under the control of a suitable pressure regulating relief valve 61 which is interposed between the supply line 58 and a drain line 62. The relief valve may be equipped with a suitable line pressure indicator 63.

Pressure fluid supplied to the regulator 46 is directed through the jet pipe element 55 thereof and is directed toward two outlet orifices 65, 66. The latter are respectively connected to the tension-increase and tension-decrease chambers of the cylinder 51 by way of lines 67 and 68. The two outlet orifices 65 and 66 are disposed in the path of lateral movement of the jet pipe 46 and are disposed in closely spaced relation to each other. It will be apparent that upon movement of the jet pipe into its tension-increase position, pressure fluid therefrom will be supplied through outlet orifice 65 by way of the line 67 to the tension-increase chamber 51a of the actuator cylinder 51. This results in an outward movement of the piston 50 and consequently of the tension pulley 53. Such movement effectively shortens the tension belt 44 and thus increases the braking force applied thereby to the running web roll 14. An increase in braking force obviously results in an increase in running web tension. Fluid contained in the tension-decrease chamber 51b of the actuator cylinder 51 is forced outwardly therefrom by way of the line 68 upon the aforesaid piston movement. Some of this fluid finds its way back into the regulator housing 56 from which it is returned to the sump 60 by way of the return line 62.

If there is an increase in running web tension above the normal setting, it is necessary to reduce the braking force applied by the belt 44 to the paper roll 14 to compensate therefor. Upon movement of the jet pipe 55 of the regulator 46 into its tension-decrease position, pressure fluid output therefrom is discharged into the outlet orifice 66 which, as previously noted, is connected to the tension-decrease chamber 51b of the actuator cylinder 51 by way of the line 68.

In the practice of the present invention, however, line 68 is connected so that the fluid is largely diverted to the return or drain line 62 with only minor pressure being applied to the decrease chamber of the actuator 51. Com-

munication with the return line is here effected by providing an interconnecting line 69 between the lines 62 and 68, the line 69 having a restriction therein indicated at 69a. Thus the major part of the pressure fluid supplied from the regulator 46 is returned to the sump 60 and only a relatively small portion finds its way into the tension-decrease chamber 51b of the cylinder 51 of the belt actuator 42. This small pressure fluid supply is sufficient to retract the actuator piston 50, but with a force substantially less than that by which the piston is extended upon supply of pressure fluid to the tension-increase chamber 51a.

As previously noted, movement of the jet pipe 55 of the hydraulic regulator 46 is under the control of the floating roller 40, with the jet pipe and the floating roller constrained to corresponding movement. Referring more specifically to the floating roller 40, it is suspended from the supporting structure 10 for limited lateral movement into and out of the web loop formed between the rollers 48 and 49. For this purpose, the floating roller is journaled adjacent the lower ends of a pair of spaced arms 70 which are rigid with a shaft 71. The latter, in turn, is journaled on the supporting structure 10. Intermediate its ends, one of the arms 70 is equipped with a push rod 72 having a flat 72a thereon adapted for engagement with a push pin 73 carried by the jet pipe regulator 46. The push pin 73 is received in a boss 74 formed integral with the regulator housing 56 and extends therethrough into the housing where it is connected to the jet pipe 55. The regulator 46 is equipped with a light compression-type spring 75 which is interposed between the jet pipe 55 and the interior of the housing 56 opposite the connection between the jet pipe and the push pin 73 to cause the jet pipe and the push pin to follow the movement of the floating roller supporting arm 70.

Means is provided for maintaining the floating rubber 40 in between the limits of its movement when the web is running at the desired normal tension. In such position, the floating roller supporting arm 70, and the jet pipe 55, too, will occupy their intermediate positions. A change in running web tension from the normal results in a corresponding deflection of the floating roller 40 and thus of the roller supporting arms 70, the push pins 72 and 73, and the jet pipe 55 so as to immediately compensate for web tension change. In the present instance, the means provided for maintaining the floating roller position comprises a hydraulic actuator 78 of the piston and cylinder type, the piston of which acts directly on the floating roller supporting arm 79. Since there is a portion of the running web W acting to pull the floating roller 40 both on the top and on the bottom thereof, then the actuator 78 must exert a force equal to approximately twice the desired normal web tension. This can be readily achieved through appropriate choice of piston and cylinder size taking into consideration hydraulic fluid pressure with which it is supplied from the same source as is the jet pipe regulator by way of pressure fluid supply lines 79 and 80. Since it is necessary only to hold the floating roller in position against the action of the running web W, pressure fluid need be supplied only to one side of the piston of the actuator 78. Thus the holding force exerted by the actuator which, as noted above, amounts to about twice the desired normal web tension, permits of control by means of a suitable pressure regulating valve 81 inserted in the supply line 79. By means of this valve, the press operator can readily alter the setting of the normal web tension to be maintained, as might be necessary for the proper operation of the printing press. Thus, adjacent the valve 81 and in the line 79, a suitable gauge or indicator 82, calibrated directly in pounds of tension pull for the running web, is provided. A drain line 83 for the pressure regulating valve 81 is provided so that when the desired tension setting of the valve is reduced, excess fluid can bleed back therethrough to the return line 62.

Upon a decrease in running web tension, a comparatively large volume of pressure fluid is at once required to quickly move the floating roller. For this purpose, a hydro-pneumatic accumulator 85 is connected into the floating roller actuator supply line 79. To accommodate the required volume of oil the supply line 80 between the accumulator 85 and the actuator 78 is made substantially larger than the supply line 79 between the pressure regulating valve 81 and the accumulator.

As previously noted, the outlet orifices 65 and 66 of the jet pipe regulator 46 are comparatively close together to the end that relatively little lateral movement is required of the jet pipe between its tension-increase and tension-decrease positions. Thus there need be relatively little movement of the floating roller suspending arms 70 to effect such jet pipe movement. By the same token, there need be but a very small lateral movement of the floating roller 40. It becomes apparent, therefore, that if such movement of the floating roller is severely limited, the inertia of the floating roller is substantially eliminated as a factor to be considered in the determination of its responsiveness to changes in web tension. With the above described construction and arrangement and the floating roller suspended for lateral swinging movement on a radius of approximately one foot (measured between the center of the roller arm supporting shaft 71 and the axis of the floating roller) an actual lateral movement of the latter axis of only one-tenth of an inch has been found satisfactory to effect proper tension control. Since such a small amount of movement produces satisfactory results and in order that floating roller inertia be eliminated as a factor, it is desirable that the permissible movement of the roller be limited substantially to that amount, for example, to one-fourth of an inch. For this purpose, suitable stop means is provided which, in the present instance, includes an outward movement-limiting stop 87 rigid with the printing press supporting structure. An inward movement-limiting stop 88, in the illustrative embodiment, is disposed within the cylinder of the floating roller actuator and is effective to limit inward movement of the actuator piston therein.

It can be shown that the running web tension should never be permitted to reach zero because if it does there will be a loss of control of the running web. If the press operator would never so operate the pressure regulating valve 81 (which controls the fluid pressure to the floating roller actuator 78) to cut off the pressure fluid supply thereto, then a certain amount of tension would always be maintained in the running web. But dependence on the operator only would be subject to the so-called "human factor." Therefore, to insure that there will be at least a minimum tension in the running web at all times even though there might be complete loss of fluid pressure in the floating roller actuator 78, means is provided to exert a slight outward force on the piston of the actuator with a corresponding outward force on the floating roller 40. In the present instance this is accomplished through the provision of a light expansion-type spring 89 which is interposed between the rear end of the actuator cylinder and the face of its piston.

Press speed is normally reduced in steps by means of the main press drive motor controller. Upon each step down in press speed there will be a corresponding momentary decrease in running web tension. In order to maintain control of running web tension by means of the tension belt 44 under such conditions with the tension control system set to maintain but minimum tension in the web, and in accordance with one of the more detailed aspects of the invention, an auxiliary shifting device is provided to effect momentary movement of the jet pipe toward its tension-increase position so as to supply pressure fluid therefrom directly into the regulator outlet orifice 65 and thence by way of the line 67 to the pressure increase chamber 51a of the belt actuator cylinder 51. As shown, this auxiliary device comprises a push-type sole-

noid 90 which is mounted so that its armature engages the floating roller supporting arm 70. It is operative to move the same outwardly to effect a corresponding movement of the jet pipe regulator push pin 73 and of the jet pipe 55. As shown in Fig. 3, the solenoid 90 is actuated through the provision of suitable contacts 91 on the press drive motor controller indicated generally at 92. The contacts 91 are closed as the motor controller arm is moved in the decrease direction by means of a rack and pinion 92a acting through a dashpot 92b. The latter is equipped with a suitable compression spring 92c which is effective to again open the contacts 91 after the closing thereof and after dashpot fluid has had sufficient opportunity to flow through its piston orifice 92d.

In the event of an emergency red button stop, as in the case of a web break, for example, it is desirable that there be immediate application of full braking force applied by the belts 44 to the web roll 14 to preclude overrunning thereof and an oversupply of paper to the press. For this purpose a push-type solenoid 95 is provided which is controlled by the emergency stop button and which acts directly on the jet pipe 55 of the regulator 46. This solenoid is effective, upon the interruption of the supply of electric power to operate the press, to move the jet pipe 55 into its full tension-increase position so as to produce a full pressure fluid supply to the tension-increase chamber 51a of the belt actuator cylinder 51. Such movement of the jet pipe causes the piston 50 and tension pulley 53 of the actuator to be moved quickly toward their fully extended positions thereby rapidly drawing up on the belt 44 so as to apply maximum braking force to the web roll 14.

Means is also provided for completely slackening off on the tension belt 44 if for any reason this is desired, as for example upon initial web threading. For this purpose, a push-type solenoid 96 under the control of a switch 96a is provided which is mounted on the jet pipe regulator housing 56. This solenoid is operative to move the jet pipe 55 into its extreme tension-decrease position so as to direct the entire pressure fluid outlet of the jet pipe into the outlet orifice 66 and thence by way of the supply line 68 to the tension-decrease chamber 51b of the belt actuator cylinder 51. This fully retracts the piston 50 and the pulley 53 so as to effectively increase the length of the belt 44.

Use of the above arrangement under a wide range of operating conditions has demonstrated that the instant tension control system is extremely sensitive and quickly responsive to web tension variations from a normal setting to compensate therefor. It might be thought that because of the slight time delay inherent in any system of this general type between the sensing of a variation in web tension and the actual compensation therefor, there would be a tendency for an oscillatory condition or hunting about the control point to obtain. It has been found, however, that any such tendency toward hunting has been entirely eliminated. Observations show that this is attributable to the restricted communication provided between the tension-decrease supply line 68 and the sump return line 62 so that the majority of pressure fluid directed by the regulator 46 toward the tension-decrease chamber 51b of the belt actuator 42 is returned to the sump 60. Thus while the belt actuator operates rapidly and with full force to compensate for a decrease in running web tension, the operation in the opposite direction, though equally quick, is of substantially less force, it being only necessary to slack off on the belt 44 so that the momentum of the running web roll is permitted to supply paper at a faster rate with a resulting decrease in web tension.

By way of summary, the press operator adjusts the pressure fluid regulator valve 81 so that the desired normal web tension obtains as indicated by the gauge 82. As long as the web tension remains constant the floating

roller actuator 78 holds the floating roller 40 in its normal central position. As a result the jet pipe 55 of the regulator 46 is also held in its central position and the supply of pressure fluid therefrom is divided substantially equally between the two outlet orifices 65 and 66. Therefore, no movement of the belt actuator piston 50 occurs, and the braking force exerted by the tension belt 44 on the web roll remains constant. Should there be a decrease in running web tension the floating roller actuator 78 operates to move the floating roller 40 to the right as shown in Fig. 2. This produces a corresponding movement of the push pin 73 to move the jet pipe 55 into its tension-increase position whereby to direct the flow of pressure fluid therefrom into outlet orifice 65, and thence by way of the supply line 67 to the tension-increase chamber 51a of the cylinder 51 of the belt actuator 42. As a result, the piston 50 and tension pulley 53 of the actuator are forced outwardly to cinch-up on the tension belt 44 with the result that an increased braking force is applied to the running web roll 14 thereby increasing the tension in the running web as it is drawn into the printing press.

As soon as the tension increase is effected, there is a corresponding pull by the running web W on the floating roller 40 to move it to the left as shown in Fig. 2 with the result that the jet pipe 55 is moved from tension-increase position toward tension-decrease position by means of the regulator spring 75. This movement continues until the desired normal running web tension is restored.

Conversely, if there should be an increase in web tension, as would be occasioned, for example, by an increase in press speed, the running web produces a movement of the floating roller toward the left, as shown in Fig. 2, against the action of the floating roller actuator 78. Such movement permits the regulator follower spring 75 to move the jet pipe 55 toward its tension-decrease position. In such position, pressure fluid from the jet pipe is directed into outlet orifice 66 and thence by way of supply line 68 partly to the tension-decrease chamber 51b of the belt actuator cylinder 51, and partly to the drain line 62. As a result, the actuator piston 50 and the tension roller 53 are permitted to retract whereby to relieve the braking force exerted by the tension belt 44 on the running web roll 14. As a result, less resistance is offered to the drawing of the web W from the paper roll 14 into the printing press and web tension decreases. As the web tension decreases, the floating roller actuator 78 effects a movement of the floating roller 40 and its supporting arm 70 toward the neutral or central position, such movement effecting a return of the jet pipe toward its central position as the desired normal web tension is restored.

From the foregoing, therefore, it will be apparent that a web tension control system constructed and arranged in accordance with the present invention is extremely sen-

5
sitive to changes in running web tension and is quickly responsive to compensate for such changes without, however, being susceptible to hunting or oscillation by "over" and "under" swinging about a desired normal tension setting.
